(57) **CLAIM**

The ornamental design for a foot cleaning device, as shown and described.

DESCRIPTION

FIG. 1 is a front perspective view of a foot cleaning device showing my new design; and,

FIG. 2 is an enlarged side elevation view thereof, the broken lines showing a zipper and support members illustrating portions of the device that form no part of the claimed design.

1 Claim, 2 Drawing Sheets

FIG. 1

FIG. 2
